UNITED STATES PATENT OFFICE

153,576

DESIGN FOR A CASE FOR A HEARING AID AMPLIFIER UNIT

Reginald B. Bland, Newport News, Va.

Application December 5, 1947, Serial No. 142,963

Term of patent 3½ years

(Cl. D26—14)

To all whom it may concern:

Be it known that I, Reginald B. Bland, a citizen of the United States, residing in the city of Newport News, county of Warwick, and State of Virginia, have invented a new, original, and ornamental Design for Case for a Hearing Aid Amplifier Unit, of which the following is a specification, reference being had to the accompanying drawing, forming part thereof, and in which

Figure 1 is a perspective view of a case for a hearing aid amplifier unit, showing my new design; and

Figure 2 is an end elevational view of the case.

The characteristic features of my design reside in the portions shown in full lines.

I claim:

The ornamental design for a case for a hearing aid amplifier unit, as shown and described.

REGINALD B. BLAND.
